UNITED STATES PATENT OFFICE.

RODERICK BEATON, OF POLLOCKSHIELDS, SCOTLAND.

BOAT LAUNCHING AND LOWERING GEAR.

1,305,643.

Specification of Letters Patent.

Patented June 3, 1919.

Application filed December 28, 1916. Serial No. 139,369.

To all whom it may concern:

Be it known that I, RODERICK BEATON, a subject of the King of Great Britain, residing at Pollockshields, in the county of 5 Renfrew, Scotland, have invented certain new and useful Improvements in and Relating to Boat Launching and Lowering Gears, of which the following is a specification.

This invention relates to improvements in 10 boat launching and lowering gear of the type in which the boat is carried by a carriage running on a pair of overhead runways or rails having pivoted extensions adapted to swing outboard from the ship's 15 side.

The object of the present invention is to provide a more simple and effective control for such boat lowering and launching arrangement whereby the structure may be of 20 considerably less weight than hitherto and the parts simple of construction and manipulation.

According to the present invention a pair of pulleys is arranged on the carriage and 25 the boat falls are passed over these, one end passing to blocks supporting the boat while the other end passes over pulleys at the end of the pivoted extensions and thence to the winch.

30 The invention is more particularly described with reference to the accompanying drawings in which:—

Figure 1 is a plan view of the arrangement.

35 Fig. 2 is a corresponding side elevation.

Fig. 3 is an end view.

The runways 1, preferably extend across the deck 2, from one side of the ship to the other, the winch gear 3, 4 being duplicated 40 so that if for any reason it is undesirable to launch boats from any one side, the winch gear of that side can be used to transport the boats into such a position that they can be taken up by launching gear of the other 45 side. The launching gear of any side is further adapted to have a sphere of operations extending at least one boat's width beyond the center line of the deck for this purpose. The pivoted extensions 5, to the 50 overhead runways on both sides of the ship can be swung out by any suitable means. For instance the runways may be pivoted about hinge pins 6 carrying a spur wheel gearing 7 with a worm having a shaft and 55 handle 8 extending inboard.

The pivoted extensions 5 of the runways

at their outer ends carry pulleys 9 over which falls 10 pass from pulleys 11 at the ends respectively of the overhead gantry or carriage 12, and thence over further pulleys 60 at the center of this to hooks on the boat, or over pulleys on this latter to hooks on the gantry.

The traveling carriage is provided with 65 rollers 13 of any desired form running along the tops of the overhead runway acting as rails. The falls having passed over the pulleys at the end of the extensions to the overhead runways, then pass preferably over a further pulley axial with the hinge 70 14 of these extensions, and thence over guide pulleys 3 suitably arranged to winch drums. Such falls 16 preferably pass from the drum over a guide pulley or pulleys, 4, thence over a pulley 15 on the carriage, thence back to 75 a fixed point 17 on the overhead runways or deck. This arrangement serves for the hauling in of the carriage and boat. The traversing of the carriage outboard is effected by the boat lowering falls 10, in that 80 the boat is lifted off the chocks as far as is limited by stops or the like on the falls, or on pulley blocks whence further operation on the boat falls will cause the carriage to pass along the overhead runways and out on 85 the extensions. As the carriage reaches the outer end of the overhead runways and on to the first part of the extensions it can be lowered to the deck level receiving passengers.

Its movements thence to the end of the extensions can be effected by releasing the brake 90 on the winch drum in question, whereby the boat will pass outboard under its own weight and lowering can then proceed from the extreme outboard position. The pivoted extensions 5 after use, can be folded in by 95 the worm gear or the like. These pivoted extensions are preferably of at least twice the width of a boat. A guide pin or roller is preferably arranged on the overhead runway, for instance on the outer post supporting it to guide the boat falls passing from the overhead carriage to prevent these falls fouling a stored boat on the deck when the boat, being launched, is at the extreme outer 100 end of the extensions.

A preferable angle for the downward inclination of the pivoted extensions to the main overhead runways normally horizontal, will be about 15° thereto.

I declare that what I claim is:—

1. A boat-launching and lowering gear,

comprising overhead runways, a carriage for the boats supported thereby, outboard extensions to said runways having a top surface inclined downward away from said runways, vertical pivots for said outboard extensions, a pair of pulleys on the carriage, boat falls passing over said pulleys, one end thereof passing to the boat, while the other end passes over the pulleys at the end of the pivoted extensions and thence backward along the runways, a second pair of pulleys on the carriage and a second set of falls passing over said pulleys, and means to connect one end of said falls to a fixed point on the overhead runways.

2. A boat-launching and lowering gear, comprising overhead runways, a carriage for the boat supported thereby, an integral triangular frame-work on each of said runways, the upper side of which frame-work is inclined outward away from said runways,

forming outboard extensions, vertical pivots supporting said extensions, a worm gearing on the base of said frame-work, a crank co-operating therewith whereby the extensions 25 may be swung outboard, pulleys on the end of said pivoted extensions, boat-falls passing over said pulleys, one end thereof passing to the boat, while the other end passes backward along the runways, a second pair of pulleys on the carriage, and a second set of falls passing over said pulleys, and means to connect one end of said falls to a fixed point on the overhead runways. 30

In witness whereof, I have hereunto signed my name this 27 day of October 1916, in the presence of two subscribing witnesses.

RODERICK BEATON.
